UNITED STATES PATENT OFFICE.

JOHN SIDNEY GOLDSMITH, OF NEW YORK, N. Y.

DESIGN FOR A BADGE.

No. 37,515.

Specification for Design.

Patented Aug. 29, 1905.

Application filed May 26, 1905. Serial No. 262,507. Term of patent 14 years.

To all whom it may concern:

Be it known that I, JOHN SIDNEY GOLDSMITH, a citizen of the United States, residing in the borough of Manhattan, in the city, county, and State of New York, have invented a new, original, and ornamental Design for Badges, of which the following is a specification, reference being had to the accompanying drawing, forming part thereof.

The figure is a plan view of a badge, showing my design.

I claim—

The ornamental design for a badge, as shown.

JOHN SIDNEY GOLDSMITH.

Witnesses:

FREDERICK C. BONNY,
F. W. BARKER.
